UNITED STATES PATENT OFFICE.

HERMANN SCHULZE, OF COSSEBANDE, BY DRESDEN, GERMANY.

BATHING-TUB.

SPECIFICATION forming part of Letters Patent No. 702,380, dated June 10, 1902.

Application filed October 3, 1901. Serial No. 77,450. (No model.)

To all whom it may concern:

Be it known that I, HERMANN SCHULZE, merchant, a subject of the King of Saxony, residing at Cossebande, by Dresden, Saxony, 5 Germany, have invented certain new and useful Improvements in Bathing-Tubs, of which the following is a specification.

This invention relates to a bath which in consequence of its peculiar shape can be used 10 as an ordinary bath as well as a sitz-bath and which is also provided with a rocking arrangement, so that the bather is able to impart wave motion to the water in the bath. The rocking arrangement consists of an approx- 15 imately crescent-shaped plate, which is put into the bath, and lying on a curved foot or support is caused to seesaw at each move- 20 ment of the bather. If the rocking arrangement is not wanted, the curved plate is sim- 25 ply removed from the bath.

The accompanying drawing illustrates a bath constructed according to this invention in longitudinal section.

The bath *a*, on account of its peculiar form 25 as regards the front wall *b*, can be employed also as a sitz-bath, so that its usefulness is greatly increased. Furthermore, in this in- 30 vention a bent plate *c*, approximately cres- cent-shaped, is provided, which preferably possesses a half-cylindrical support or projec-

tion *d*, on which the former rests when placed in the bath. The plate *c* is approximately of the same width as the bath, and the bather when using this arrangement by causing this plate to seesaw on *d* is enabled to impart 35 wave motion to the water. If this arrangement is not wanted, it is simply taken out of the bath.

Having now particularly described and as- 40 ccertained the nature of my said invention and in what manner the same is to be performed, I declare that what I claim is—

A bath-tub, the bottom and one end of which are defined by an unbroken curve, and an ap- 45 proximately crescent-shaped plate in said tub having a semicylindrical foot on its under side located at one side of the center of gravity of said plate and the rear upper side of said plate being located normally above the upper edge of the bath-tub, whereby said plate is 50 adapted to receive the back and shoulders of a user.

In testimony whereof I have hereunto set my hand in presence of two subscribing wit- 55 nesses.

HERMANN SCHULZE.
